(57) **CLAIM**

The ornamental design for a shed, as shown and described.

DESCRIPTION

FIG. 1 is a top perspective view of a shed, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlargement of FIG. 1.

The drawings contain symbolic break lines in FIGS. 1-2 and 5-8. The portion between the break lines forms no part of the claimed design. The dash-dot broken lines in FIGS. 1 and 9 represent the bounds of the detail views and form no part of the claimed design.
